AUXILIARY BOBBIN SUPPORT FOR USE ON
THE SHANK OF A BOBBIN HOLDER

Fritz Lambach, Tenafly, N. J.

Application October 16, 1944, Serial No. 558,838

19 Claims. (Cl. 242—130)

1

My invention relates to textile machines, and more particularly to supports for bobbins.

The bobbins available in the trade have cylindrical tubes or conical tubes, and the conical tubes are made in a great variety of different shapes.

An object of my invention is to provide an auxiliary bobbin support, by means of which a bobbin holder made for normally supporting a bobbin with a cylindrical tube may be readily adapted to the support of bobbins with conical tubes of various shapes, so that a textile machine, for example a creel, may be used for any type of bobbins available in the market.

Another object of my invention is to provide such an auxiliary bobbin support or adapter, which may be readily mounted on a bobbin holder constructed for the support of bobbins with cylindrical tubes, when such a bobbin holder is to be used for bobbins with conical tubes.

A further object of my invention is to provide an auxiliary bobbin support or adapter of above described type, which is of such a structure, that it assures a stable support of conical tubes of various shapes.

Still another object of my invention is to provide such an auxiliary bobbin support or adapter, which may be manufactured at low costs.

With the above and other objects of the invention in view, the invention consists in the novel construction, arrangement and combination of various devices, elements and parts as set forth in the claims hereof, certain embodiments of the same being described in the specification and being illustrated in the accompanying drawings forming part of this specification, wherein:

Fig. 1 is a top plan view of a bobbin holder for the support of a bobbin with a cylindrical tube, some parts being shown in section,

Fig. 2 is a top plan view, partly in section, of an auxiliary bobbin support or adapter according to the invention,

Fig. 3 is an elevational view of the head of the adapter shown in Fig. 2, a portion of an element being broken away,

Fig. 4 is an elevational view of the base of the adapter shown in Fig. 2, and

Fig. 5 is a top plan view, partly in section, of the bobbin holder shown in Fig. 1 with an adapter shown in Fig. 2 mounted thereon.

Referring now to the drawings, 10 generally indicates a bobbin holder comprising a shank 12, one end of which is threaded into a threaded bore of an arm 14 for a rigid connection therewith. The shank 12 is provided with longitudinal re-

2

cesses 16 and 18 at opposite sides of its circumference; said recesses are connected with each other by a transverse bore 20. A spring 22 made of a resilient wire bent in a suitable shape passes through said bore 20 and is partially engaged with said recesses 16 and 18. The free ends 24 and 26 of said wire spring 22 are held in slidably engagement with said recesses 16 and 18 by means of a holding element 28 screwed on a threaded portion of the shank 12. The arm 14 has a bore 30 at its free end for engagement with a rod of a textile machine, for example a creel, and the bobbin holder 10 may be held in its position on such a rod by means of a spring 32 secured to the arm 14 by means of a screw 34.

The described bobbin holder 10 may be used for the support of a bobbin 36 with a cylindrical tube 38. When such a bobbin 36 with a cylindrical tube 38 is placed on the shank 12 of the bobbin holder 10, the spring 22 is somewhat compressed while its ends 24, 26 slide toward the left hand end of the shank (as viewed in Fig. 1); the spring 22 urging against the inner wall of the cylindrical tube 38 holds the bobbin 36 on the shank 12 of the bobbin holder 10.

Hereinafter I describe an auxiliary bobbin support or adapter according to the invention, by means of which above described bobbin holder may be adapted to the support of bobbins with conical tubes.

According to Figs. 2-4, the adapter 40 comprises a head 42, a base 44, and a flexible or compressible cage 46.

The head 42 comprises a disc 48 having a center bore 50 and having four longitudinal recesses 52 on its circumference. A set screw 54 is threaded into a threaded radial bore 56 of the disc 48. Furthermore, a teetted washer 58 or the like is mounted on the head 42; said teetted washer is secured to the disc 48 in a manner to be described hereinafter.

The base 44 comprises a disc 60 having a center bore 62 and a flange 64 provided with four recesses 66. A resilient split ring 68 is arranged within said flange so as to form an abutment.

The cage 46 is made of two resilient wires 70 and 72, which are arranged in planes being at an angle of 90° relative to each other. Each wire is in engagement with opposite recesses 52 on the disc 48 and with opposite spaces between teeth of the teetted washer 58. The wires are firmly held in engagement with said recesses 52 by an inward hammering of the edges of the recesses as indicated at 74. Therefore, the cage 46 formed by said pair of wires 70, 72 is rigidly connected with the head 42, and the teetted washer 58 embraced

by a portion of said wires 70, 72 is firmly secured to the disc 48 of the head. The end portions 76 of the wire 70 and the end portions 78 of the wire 72 are slidably engaged with the recesses 66 of the flange 64 of the disc 60, so that they may be moved inwardly from the position shown in Fig. 2 into the position shown in Fig. 5 when the flexible and resilient cage 46 is compressed. Furthermore, the ends 80 of said end portions 76 and the ends 82 of said end portions 78 are bent at a right angle, so that said ends 80 and 82 form stops for engagement with the split ring 68, when the cage 46 is released as shown in Fig. 2. The wires 70 and 72 are bent in suitable manner as shown in the drawings, so that the cage 46 formed by said wires is tapered from a point 84 adjacent the base 44 toward the head 42.

When the bobbin holder 10 shall be used for carrying bobbins with a conical tube, the above described adapter 40 is mounted on the shank 12 by engaging the shank with the aperture 62 in the base 44, shifting the adapter 40 over the compressible bowed springs 22, engaging the shank with the aperture 50 in the head 42, and tightening the set screw 54 for engagement with a recess 86 on the shank. Thus, the adapter 40 is firmly held on the shank 12 of the bobbin holder 14. During the mounting of the adapter 40 on the shank 12, the bowed springs 22 are compressed by the wall of the aperture 62 sliding along the springs 22; when the adapter 40 is in its place on the shank 12 as shown in Fig. 5, the springs may expand into their original position. Now, when a bobbin 88 with a conical tube 90 of paper or cardboard is placed on the cage 46, the resilient wires 70 and 72 thereof are compressed and are brought into the position shown in Fig. 5. The resilient wires urge against the inner wall of the conical tube 70, so that they hold the latter on the adapter. Furthermore, the teeth of the teetted washer 58 bite to a certain degree into the material of the wall of the conical tube 70 so as to assist in the holding of the bobbin on the adapter. It has been found that the teetted washer 58 is extremely useful for conical tubes with a great inclination of the wall of the tube.

As will be readily understood from above, the slideable connection of the end portions 76 and 78 of the wires 70 and 72 with the base 44 permits the support of bobbins with conical tubes of various shapes. The greater the inclination of the wall of the tube, the smaller the inward movement of the end portions 76, 78 when the bobbin with the conical tube is placed on the cage 46 of the adapter 40.

I have described a preferred embodiment of my invention, but it is clear that numerous changes and omissions may be made without departing from the spirit of my invention.

What I claim is:

1. An auxiliary bobbin support adapted to be mounted on a bobbin holder having a shank provided with bowed springs having their free ends slidably engaging the shank for receiving a cylindrical bobbin tube, comprising a substantially conical-shaped body for the support of a conical bobbin tube, said body having a first aperture near one end adapted to be passed over said bowed springs into a mounting position near one end of said shank, and said body having a second aperture spaced from said first aperture and adapted to be engaged with the other end of said shank.

2. An auxiliary bobbin support adapted to be

mounted on a bobbin holder having a shank provided with bowed springs for receiving a cylindrical bobbin tube, comprising a substantially conical-shaped body for the support of a conical bobbin tube, said body having a first aperture near one end adapted to be passed over said bowed springs into a mounting position near one end of said shank, said body having a second aperture spaced from said first aperture and adapted to be engaged with the other end of said shank, said body being hollow between said apertures and its hollow portion being spaced from the springs so that said bowed springs may expand into their original position after the passing of said first aperture over said springs.

3. An auxiliary bobbin support adapted to be mounted on a bobbin holder having a shank provided with bowed springs for receiving a cylindrical bobbin tube, comprising a substantially conical-shaped body for the support of a conical bobbin tube, said body having a first aperture near one end adapted to be passed over said bowed springs into a mounting position near one end of said shank and having a second aperture spaced from said first aperture and adapted to be engaged with the other end of said shank, and means associated with said body for rigidly connecting the same with said shank.

4. An auxiliary bobbin support adapted to be mounted on a bobbin holder having a shank provided with bowed springs for receiving a cylindrical bobbin tube, comprising a body having a large end and a small end and being substantially conical-shaped for the support of a conical bobbin tube, said body having a first aperture near the large end adapted to be passed over said bowed springs into a mounting position near one end of said shank and having a second aperture spaced from said first aperture and adapted to be engaged with the other end of said shank, and a stationary teetted element arranged near said small end of said body and connected to the latter for engagement with the material of the inner wall of a conical bobbin tube placed on said body.

5. An auxiliary bobbin support adapted to be mounted on a bobbin holder having a shank provided with bowed springs for receiving a cylindrical bobbin tube, comprising a body having a large end and a small end and being substantially conical-shaped for the support of a conical bobbin tube, said body having a first aperture near the large end adapted to be passed over said bowed springs into a mounting position near one end of said shank and having a second aperture spaced from said first aperture and adapted to be engaged with the other end of said shank, and a teetted washer arranged near said small end of said body for engagement with the material of the inner wall of a conical bobbin tube placed on said body.

6. An auxiliary bobbin support adapted to be mounted on a bobbin holder having a shank provided with bowed springs for receiving a cylindrical bobbin tube, comprising a body having a large end and a small end and being substantially conical-shaped for the support of a conical bobbin tube, said body having a first aperture near its large end adapted to be passed over said bowed springs into a mounting position near one end of said shank and having a second aperture spaced from said first aperture and adapted to be engaged with the other end of said shank, and the supporting portion of said body which is arranged near the large end thereof for engage-

ment with a substantial length of said conical bobbin tube being made of resilient material and being compressible so as to take bobbins of various shapes.

7. An auxiliary bobbin support adapted to be mounted on a bobbin holder having a shank provided with bowed springs for receiving a cylindrical bobbin tube, comprising a body having a large end and a small end and being substantially conical-shaped for the support of a conical bobbin tube, said body having a first aperture near its large end adapted to be passed over said bowed springs into a mounting position near one end of said shank and having a second aperture spaced from said first aperture and adapted to be engaged with the other end of said shank, the supporting portion of said body which is arranged near the large end thereof for engagement with a substantial length of said conical bobbin tube being made of resilient material and being compressible so as to take bobbins of various shapes, and a stationary toothed element arranged near said small end of said body and connected to the latter for engagement with the material of the inner wall of a conical bobbin tube placed on said body.

8. An auxiliary bobbin support adapted to be mounted on a bobbin holder having a shank provided with bowed springs for receiving a cylindrical bobbin tube, comprising a body having a large end and a small end and being substantially conical-shaped for the support of a conical bobbin tube, said body having a first aperture near its large end adapted to be passed over said bowed springs into a mounting position near one end of said shank and having a second aperture spaced from said first aperture and adapted to be engaged with the other end of said shank, the supporting portion of said body which is arranged near the large end thereof for engagement with a substantial length of said conical bobbin tube being made of resilient material and being compressible so as to take bobbins of various shapes, and a toothed washer arranged near said small end of said body and connected to the latter for engagement with the material of the inner wall of a conical bobbin tube placed on said body.

9. An auxiliary bobbin support adapted to be mounted on a bobbin holder having a shank provided with bowed springs for receiving a cylindrical bobbin tube, comprising a head, a base, and a compressible cage made of resilient wire material, one end of said cage being connected with said head, the other end of said cage being connected with said base, said cage being tapered from a point adjacent said base toward said head for the support of a conical bobbin tube, said base having a first aperture adapted to be passed over said bowed springs into a mounting position near one end of said shank, and said head having a second aperture adapted to be engaged with said shank.

10. An auxiliary bobbin support adapted to be mounted on a bobbin holder having a shank provided with bowed springs for receiving a cylindrical bobbin tube, comprising a head, a base, a compressible cage made of resilient wire material, one end of said cage being connected with said head, the other end of said cage being connected with said base, said cage being tapered from a point adjacent said base toward said head for the support of a conical bobbin tube, said base having a first aperture adapted to be passed over said bowed springs into a mounting

position near one end of said shank, said head having a second aperture adapted to be engaged with said shank, and means associated with said head-base-cage assembly for rigidly connecting the same with said shank.

11. An auxiliary bobbin support adapted to be mounted on a bobbin holder having a shank provided with bowed springs for receiving a cylindrical bobbin tube, comprising a head, a base, and a compressible cage made of resilient wire material, one end of said cage being rigidly connected with said head, the other end of said cage being movably engaged with said base, said cage being tapered from a point adjacent said base toward said head for the support of a conical bobbin tube, said base having a first aperture adapted to be passed over said bowed springs into a mounting position near one end of said shank, and said head having a second aperture adapted to be engaged with said shank.

12. An auxiliary bobbin support adapted to be mounted on a bobbin holder having a shank provided with bowed springs for receiving a cylindrical bobbin tube, comprising a head, a base having a plurality of springs at its circumference, and a compressible cage made of a plurality of resilient wires, one end of said cage being rigidly connected with said head, the ends of said wires at the other end of said cage being bent so as to extend in a substantially radial direction, said openings at the circumference of said base slidably receiving said radially extending ends of the wires of the cage whereby the cage may be compressed without a substantial displacement of said base in the direction of the longitudinal axis of said cage, said cage being tapered from a point adjacent said base toward said head for the support of a conical bobbin tube, said base having a first aperture adapted to be passed over said bowed springs into a mounting position near one end of said shank, and said head having a second aperture adapted to be engaged with said shank.

13. In an auxiliary bobbin support, as claimed in claim 12, said base including a flanged disc having a plurality of openings in its flange slidably receiving the ends of the plurality of wires forming the cage, and said ends of said wires being bent so as to form stops for engagement with a stationary part on said flange.

14. In an auxiliary bobbin support as claimed in claim 12, said base including a flanged disc having a plurality of recesses slidably receiving the ends of the plurality of wires forming the cage, a split ring arranged on said disc for engagement with the flange thereof, and the ends of said wires being bent so as to form stops for engagement with said split ring.

15. An auxiliary bobbin support adapted to be mounted on a bobbin holder having a shank provided with bowed springs for receiving a cylindrical bobbin tube, comprising a head, a base, a compressible cage made of resilient wire material, one end of said cage being connected with said head, the other end of said cage being connected with said base, said cage being tapered from a point adjacent said base toward said head for the support of a conical bobbin tube, a stationary toothed element mounted on said head for engagement with the material of the inner wall of a conical bobbin tube placed on said cage, said base having a first aperture adapted to be passed over said bowed springs into a mounting position near one end of said shank, and said head having a second aperture adapted to be engaged with said shank.

16. An auxiliary bobbin support adapted to be mounted on a bobbin holder having a shank provided with bowed springs for receiving a cylindrical bobbin tube, comprising a head, a base, a compressible cage made of resilient wire material, one end of said cage being connected with said head, the other end of said cage being connected with said base, said cage being tapered from a point adjacent said base toward said head for the support of a conical bobbin tube, a toothed washer mounted on said head for engagement with the material of the inner wall of a conical bobbin tube placed on said cage, said base having a first aperture adapted to be passed over said bowed springs into a mounting position near one end of said shank, and said head having a second aperture adapted to be engaged with said shank.

17. An auxiliary bobbin support adapted to be mounted on a bobbin holder having a shank provided with bowed springs for receiving a cylindrical bobbin tube, comprising a head, a base, a compressible cage made of resilient wire material, one end of said cage being rigidly connected with said head, the other end of said cage being movably engaged with said base, said cage being tapered from a point adjacent said base toward said head for the support of a conical bobbin tube, a stationary toothed element mounted on said head for engagement with the material of the inner wall of a conical bobbin tube placed on said cage, said base having a first aperture adapted to be passed over said bowed springs into a mounting position near one end of said shank, and said head having a second aperture adapted to be engaged with said shank.

18. An auxiliary bobbin support adapted to be mounted on a bobbin holder having a shank provided with bowed springs for receiving a cylindrical bobbin tube, comprising a head, a base, a compressible cage made of resilient wire material, one end of said cage being rigidly connected with said head, the other end of said cage being movably engaged with said base, said cage being tapered from a point adjacent said base toward said head for the support of a conical bobbin tube, a toothed washer mounted on said head for engagement with the material of

the inner wall of a conical bobbin tube placed on said cage, said base having a first aperture adapted to be passed over said bowed springs into a mounting position near one end of said shank, and said head having a second aperture adapted to be engaged with said shank.

19. An auxiliary bobbin support adapted to be mounted on a bobbin holder having a shank provided with bowed springs for receiving a cylindrical bobbin tube, comprising a head, a base having a plurality of openings at its circumference, a compressible cage made of a plurality of resilient wires, one end of said cage being rigidly connected with said head, the ends of said wires at the other end of said cage being bent so as to extend in a substantially radial direction, said openings at the circumference of said base slidably receiving said radially extending ends of the wires of the cage whereby the cage may be compressed without a substantial displacement of said base in the direction of the longitudinal axis of said cage, said cage being tapered from a point adjacent said base toward said head for the support of a conical bobbin tube, and a toothed element mounted on said head for engagement with the material of the inner wall of a conical bobbin tube placed on said cage, said base having a first aperture adapted to be passed over said bowed springs into a mounting position near one end of said shank, and said head having a second aperture adapted to be engaged with said shank.
